UNITED STATES PATENT OFFICE.

CHESLEY T. SMALL, OF ST. LOUIS, MISSOURI, ASSIGNOR, BY MESNE ASSIGNMENTS, TO AUTOMATIC CAN FILLING MACHINERY COMPANY, OF NEWARK, NEW JERSEY, A CORPORATION OF NEW JERSEY.

CAN-CAPPING MACHINE.

1,208,848.

Specification of Letters Patent. Patented Dec. 19, 1916.

Application filed August 21, 1912. Serial No. 716,257.

To all whom it may concern:

Be it known that I, CHESLEY T. SMALL, a citizen of the United States of America, residing at the city of St. Louis, State of Missouri, have invented a certain new and useful Can-Capping Machine, of which the following is such a full, clear, and exact description as will enable anyone skilled in the art to which it appertains to make and use the same, reference being had to the accompanying drawings, forming part of this specification.

My invention relates to a can capping machine and more particularly to the improvement on that form of machine shown and described in my prior application Serial Number 659,224, filed November 8, 1911.

The principal object of my invention is to adapt the machine above referred to, to use in applying slip covers to cans or other receptacles.

My invention also relates to certain details of construction, all of which will be described in the following specification and pointed out in the claims affixed hereto.

In the accompanying drawings, which illustrate one form of machine made in accordance with my invention, Figure 1 is a front elevation of the front portion of the machine; Fig. 2 is a top plan view partly in section; Fig. 3 is an enlarged perspective view of one of the can holders; Fig. 4 is an enlarged sectional view of the cap feeding mechanism; Fig. 5 is a top plan view of the center of the parts shown in Fig. 4; Fig. 6 is a cross section of the cap chute; and Figs. 7, 8 and 9 are enlarged views of the tool for turning over the upper edge of the cans.

Like marks of reference refer to similar parts in the several views of the drawings.

10 represents the base of the machine on which are carried two uprights 11 and 12. Carried by the upright 11 is an adjustable bracket 13 which carries the can supporting 45 and can feeding mechanism. Adjustably carried in the upright 12 is arm 14 which carries the tool holders and operating device therefor. The general construction of all of these parts is the same as that set 50 forth in my prior application above referred to and will not be described in detail. Briefly, they are as follows:

15 is a rotary table receiving the empty cans from the chute 16 and delivering the

same to a stationary table 17 on to which 55 the cans are guided by a series of adjustable rams 18. Arranged above the table 17 is a rotary turret 20 shown in dotted lines in Fig. 1, which turret carries a number of can holders 21 which are adapted to be moved 60 vertically into and out of engagement with the cans carried on the table 17 by means of a rotary member 22. These can holders 21 differ from the can holders described in my prior application in that they are provided with a slot 23 adapted to receive a division plate as will be hereinafter more fully described. In addition to the turret 20, the arm 13 carries three vertical plungers 24, 25 and 26, together with the operating 70 mechanism therefor. The spindle 24, in addition to moving vertically, is also adapted to be rotated by gearing as has been described in my prior application. The spindle 24 carries on its lower end a forming 75 tool, shown in detail in Figs. 7, 8 and 9.

The spindle 24 has secured to it by means of pins 30 two collars 31. Arranged between the collars 31 is a rotary collar 32 provided with trunnions 33 engaged by the 80 bifurcated end of the operating lever 34 which moves the stem or spindle 24. The collar 32, as best shown in Fig. 7, is preferably made in two parts to enable it to be readily applied to the stem. The lower end 85 of the stem 24 is reduced, as shown at 35 in Fig. 7, and is surrounded by means of sleeve 36, the exterior of which is threaded. Secured to the lower end of the reduced portion 35 of the stem 24 by means of pin 90 37 is a plate 38. This plate 38 has slidingly mounted on it a pair of blocks 39 carrying vertically arranged forming wheels 40 which are adapted to engage with the upper edge 95 of the can and turn the same over slightly so as to facilitate the application of the slip covers.

41 are links which are pivoted at one end to upward projections of the blocks 39, and at the other end to levers 42 which are in 100 turn pivoted by pins 43 to upwardly extending lugs 44 carried on the plate 38. The levers 42 are connected by means of links 45 with the sleeve 36 surrounding the lower end of the stem. The pivoted pins 46 of 105 the links 45 are held in position by a collar 47 surrounding the said sleeve 36 and locked in position by means of lock nuts 48.

49 is a housing surrounding the operating parts of the devices and engaged at its upper end by means of a nut 50 threaded on the sleeve 36. The upper end of the sleeve 36 is 5 also engaged by a nut 51 and the lower end of the main part of the stem 24 by nut 52. By adjusting the nuts 50, 51 and 52, it will be evident that the sleeve 36 can be moved longitudinally relative to the stem 35 so as 10 to move the blocks 39 toward or away from the center line of the tool and thus adjust the tool for use with cans of various sizes.

While I prefer to rotate the tool in order to turn over the upper edge of the can, as 15 shown in the construction illustrated, it will be evident that the tool might be allowed to remain stationary and the can rotated by means of the check 55, in Fig. 1, as has been described in connection with my prior application above referred to.

After the edge of the can has been turned over by the tool above described, it is brought forward into position to receive one of the slip covers from the cover chute as is 25 best shown in Fig. 4 of the drawings. In this position, the slot 23 in the can holder 21 is engaged by means of a division plate 56. This division plate receives the can cap 57, shown in dotted lines in Fig. 4, and holds 30 the same up out of engagement with the can top until the said cap has had time to assume the proper position on the plate after which, by the forward movement of the holder, the plate is withdrawn so as to allow the can cap 35 to settle down and properly seat itself over the top of the can.

The cap feeding mechanism, shown in Figs. 4, 5 and 6, differs in some details from the cap feeding mechanism described in my 40 prior application hereinbefore described. The cap chute is formed as follows: A number of brackets 58 are provided to each of which are adjustably secured a number of divided cross pieces 59 by means of cross 45 screws 60, as best shown in Fig. 6. Each of these divided cross pieces 59 have secured to them removable tracks 61. The brackets 58 carry screws 62 by means of which side pieces 63 are carried and adjusted 50 in relation to the tracks 61. These side pieces 63 are also provided with removable tracks 64 which coöperate with the tracks 61 to form the guide-way for the can caps. The feed of the can caps through the cap chute 55 is controlled by a rocking lever 65 similar to that described in my prior application. The manner of rocking the rocking lever in the present instance is different from that in my prior application. The rocking lever 60 65 is provided with an antifriction roller 66 which bears upon one end of the arm 67 pivoted at 68 to a bracket 69 carried by the cap chute. Secured to this bracket 69 by means of a pivot 70 is an arm 71, the end of which 65 projects into the path of the cans which are

carried on the table 17. The arm 71 has a rearwardly projecting portion 72 which is connected by means of a threaded rod 73 with the arm 67 which bears upon the roller 66. An adjustable connection between the 70 part 72 and the rod 73 is obtained by a nut 74. The movement of the arm 71 in one direction is limited by a set screw 75 which bears against the projecting finger 76 on the arm 71. It will be evident that when a can 75 body comes into contact with the end of the arm 71, the movement will be communicated through the rearwardly projecting portion 72 and the rod 73 to the arm 67 which bears on the antifriction roller 66 and thus 80 causes the lever 65 to feed forward a new cap and deposit the same on the division plate 56. After the holder 21 containing the cap is fed forward so as to disengage the division plate 56 from the slot 23, the cap 85 will fall down into position over the top of the can and will be forced down over the can by means of a tool or hammer 78 carried on the lower end of the reciprocating rod 25. After the can is fed forward to the 90 operating position, the holder 21 is partially lifted, the can is again operated upon by a weight or hammer 79 carried on the lower end of the rod 26. In order to insure the disengagement of the can from the holder 21, 95 when said holder is lifted to its highest position, I secure to the rod 26 by means of a rigid connection 80 a rod 81 which carries a weight or hammer 82 for engaging the can and discharging the same from the holder 100 21 in case the can should stick in the holder after it has reached its highest position. The can after being discharged from the holder is carried away from the machine by means of a conveyer 83.

The various details of my machine not described in the present application are the same as those described in my prior application hereinbefore referred to, and consequently need not be described in the present 110 application.

Having fully described my invention, what I claim as new and desire to secure by Letters Patent of the United States is:

1. In a can capping machine, the combination with a can holder movable vertically to engage the can, of means for supporting a cap in said holder above the can, and means for moving the holder laterally relative to the supporting member for allowing the 115 cap to drop upon the can.

2. In a can capping machine, the combination with a can holder movable vertically to engage the can, of a plate for supporting a cap in the holder above the can, and means 120 for moving said holder laterally relative to the plate to allow the cap to drop upon the can.

3. In a can capping machine, the combination with a plurality of holders movable 130

vertically to engage the cans, of means for rotating said holders, said holders being each provided with a slot, a stationary division plate adapted to enter said slots and support a cap in the holder, and feeding mechanism for delivering the caps to said holders while coöperating with said plate.

4. In a can capping machine, the combination with a can holder, of a chute for delivering caps to said holder, a rocking member provided with fingers projecting into said chute to control the feed of the caps, one of said fingers being adapted to move in front of one of the caps simultaneously with the

15 withdrawal of the other finger from in front of another cap, a yielding member arranged in the path of the can carried by said holder, and adjustable connections between said members.

20 5. In a can capping machine, the combination with a can holder, of a chute for delivering caps to said holder, a rocking member provided with fingers projecting into said chute to control the feed of the caps, a yielding member arranged in the path of the can carried by said cap, and an adjustable arm carried by said yielding member and bearing on said rocking member to actuate the latter.

25 6. In a can capping machine, the combination with a can holder, of a chute for delivering caps to said holder, a rocking member provided with fingers projecting into said chute and controlling the feed of the caps, one of said fingers being adapted to move in front of one of the caps simultaneously with the withdrawal of the other finger from in front of another cap, a pivoted member arranged in the path of the can carried by said holder and actuating said

35 rocking member, and an adjustable stop for

limiting the movement of said pivoted member in one direction.

7. In a can capping machine, the combination with a can holder, of a chute for delivering caps to said holder, a rocking member 45 provided with fingers projecting into said chute to control the feed of the caps, an anti-frictional roll carried by said member, an arm bearing on said anti-frictional roll, a pivoted finger arranged in the path of the 50 can carried by said holder, adjustable connections between said arm and finger, and a stop for limiting the movement of said finger.

8. In a cap chute for can machines, the 55 combination with adjustable side members, of removable downwardly projecting tracks carried thereby and coöperating with the caps in said chute.

9. In a cap chute for can machines, the 60 combination with brackets, of adjustable cross bars carried by said brackets, and removable upwardly projecting tracks carried by said cross bars and coöperating with the 65 caps in said chute.

10. In a cap chute for can machines, the combination with brackets, of adjustable cross bars carried by said brackets, removable tracks carried by said cross bars and coöperating with the caps in said chute, side pieces 70 carried by said brackets, and removable tracks carried by said side pieces and coöperating with the caps in said chute.

In testimony whereof, I have hereunto set 75 my hand and affixed my seal in the presence of the two subscribing witnesses.
